[57] **CLAIM**

The ornamental design for a combined metronome and golf club head, as shown and described.

DESCRIPTION

FIG. 1 is a perspective view of a combined metronome and golf club head showing our new design;

FIG. 2 is a left side elevational view thereof;

FIG. 3 is a front elevational view;

FIG. 4 is a rear elevational view;

FIG. 5 is a top plan view; and,

FIG. 6 is a bottom plan view thereof.

The broken line showing of a shaft and fragmented human figure is for illustrative purposes only and forms no part of the claimed design.
